(57) **CLAIM**

The ornamental design for a retractable gate, as shown and described.

DESCRIPTION

FIG. 1 is a top, front, left side perspective view of a retractable gate in retracted status, showing my new design; FIG. 2 is a bottom, rear, right side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is another front, left side perspective view of the retractable gate in extended status; FIG. 10 is an enlarged view of portion 10 in FIG. 2; and, FIG. 11 is an enlarged view of portion 11 in FIG. 9. The broken lines depict portions of the retractable gate that form no part of the claimed design.
